Attorney

UNITED STATES PATENT OFFICE.

ANTHONY E. COYNE, OF MARION, ILLINOIS.

SHIELD OR PROTECTOR.

1,221,513.

Specification of Letters Patent.

Patented Apr. 3, 1917.

Application filed June 13, 1916. Serial No. 103,519.

To all whom it may concern:

Be it known that I, ANTHONY E. COYNE, a citizen of the United States, residing at Marion, in the county of Williamson and State of Illinois, have invented certain new and useful Improvements in Shields or Protectors; and I do hereby declare the following to be a full, clear, and exact description of the invention, such as will enable others skilled in the art to which it appertains to make and use the same.

My invention relates to new and useful improvements in shields or protectors and more particularly to that class adapted to be used by a person while washing the face or head and my object is to provide a device that may be clamped around the wrists to prevent water from passing from the hand on to the arms while using the hands for bathing the face or head.

A further object is to provide a flexible or resilient lining for the protector whereby the circulation from the arms and hands will be uninterrupted when the protectors are clamped upon the wrists.

A further object is to provide a covering of rubber or similar substance for parts of the protector and so construct the same that the water will be drained from the protector in such manner as not to come in contact with the garments worn by the person using the protector.

And a further object is to provide means for quickly attaching or detaching the protector.

Other objects and advantages will be hereinafter set forth and more particularly pointed out in the accompanying specification.

In the accompanying drawings which are made a part of this application,

Figure 1 is a perspective view showing the device applied to use.

Fig. 2 is a sectional view thereof as seen on line 2—2, Fig. 1, and

Fig. 3 is a sectional view as seen on line 3—3, Fig. 2.

Referring to the drawings in which similar reference numerals designate corresponding parts throughout the several views, 1 indicates the frame of the protector which is preferably formed in sections 2 and 3 which, when properly assembled, form a substantially oval band, said sections having ears

4 and 5 respectively which are pivotally secured together by extending a pin 6 transversely through said ears.

Surrounding that portion of the pin 6 between the ears 5 is a coil spring 7, one end 8 of which is extended at right angles to the trend of the pin and rested upon the outer face of the section 2, while the opposite end 9 is extended in the opposite direction and rested upon the face of the section 3, whereby said spring will direct pressure against said sections and normally hold the section 3 in closed position.

Placed within the protector is a lining 10 of any suitable flexible material and over said lining is placed the covering 11 preferably of rubber, the outer edge of said covering having a flange portion 12 which fits over the edge of the lining and frame of the protector, said flange being concave or cupped to form a channel 13 which will serve to convey any water flowing against the flange into a trough 14 of an extension 15 preferably formed integral with the flange.

In applying my device to use, the section 3 is thrown to an open position and the frame then introduced around the wrist in such manner that the extension 15 will extend downwardly or below the wrist and when outward pressure is released from the section 3, the spring will instantly clamp the frame around the wrist with sufficient force to hold the shield in engagement with the wrist and prevent water from passing between the shield or protector and the wrist.

It frequently occurs that when the hands have been immersed in water and raised to wash the face or head that portions of the water will drain downwardly upon the wrist and come in contact with the garments worn by the person, but by first clamping one of the protectors around each wrist the water is arrested in its passage and caused to drain off through the channels and trough, the extensions 15 being of sufficient length to carry the water beyond the sleeves of the garment.

This device not only protects the garments of the wearer and saves laundry bills, but eliminates the possibility of catching cold by wearing garments that have become dampened while washing the face or hands and it will likewise be seen that by

providing the yielding or flexible lining, the circulation of the blood through the arm and hand will be uninterrupted, although the frame is clamped into engagement with the wrist with sufficient force to hold the protector in position on the wrist.

It will likewise be seen that this device can be very cheaply constructed and will be practically indestructible from use and that the same can be quickly engaged with the wrist or disengaged therefrom.

What I claim is:—

1. In a protector of the class described, the combination with a frame formed in sections and means to hingedly secure said sections together, of a flexible lining within the frame and a non-porous covering for said lining and edges of the frame, the outer edge of said covering having a flange concave in cross section to form a channel, and an extension having a trough formed therein communicating with said channel, whereby water contacting said protector will be

carried from the channel to said trough and discharged from the end of the extension. 25

2. In a protector of the class described, the combination with a frame formed in sections and means to hingedly secure the sections together and a spring adapted to normally hold the sections clamped around the wrist of the wearer, of a lining interiorly of said frame, a non-porous covering extending over said lining and over the ends of the frame, a flange at the outer end of the covering arranged to form a channel, and an extension on said flange having a trough formed therein communicating with said channel. 30 35

In testimony whereof I have signed my name to this specification in the presence of two subscribing witnesses.

ANTHONY E. COYNE.

Witnesses:

ARTHUR V. RICE,
BEN OLIVER.
